UNITED STATES PATENT OFFICE.

DAVID BARATT, OF ROXBURY, MASSACHUSETTS.

SECTIONAL IMPRESSION TRAY.

Application filed March 9, 1925. Serial No. 14,214.

My present invention relates to dental impression trays, and more particularly to impression trays of the sectional type.

One of the principal difficulties encountered in the dental art, exists in the making of impressions of a patient's mouth, for the purpose of installing bridge work, or the like. There have been many impression trays, and some sectional impression trays, but none of these, so far as I am aware, have been satisfactory in their operation.

In taking an impression for the purpose of bridge work, for example, an impression tray is filled with plaster of Paris, preferably, in a moldable condition, and is then placed in position over the portion of the patient's teeth and gums where it is desired to insert bridge work. Upon the hardening of the plaster of Paris, it is then removed from the mouth, and a form, simulating that portion of the patient's mouth from which the impression has been taken, is made. However, the impression molds at present in use, have been impractical, for many reasons. Principally among these is that where a space of missing teeth is V-shaped, or where the teeth are bell-shaped, the plaster either breaks or chips away, thus leaving an imperfect impression, or it is liable to pull out or injure the patient's teeth, in any event, with pain and suffering resulting to the patient.

An important object of my present invention, therefore, is the devising of an impression tray, which will take as nearly as perfect an impression as possible, with the least inconvenience, discomfort and suffering to the patient.

To this end I have devised my novel sectional impression tray, which comprises two body portions adapted to interlock with each other, and receive plaster of Paris, or other impression making composition therein, and have provided these body members with a plurality of hinged plates. The purpose and function of these plates is that the tray may be changed to fit any desired space or cavity between a patient's teeth. If the space of which an impression is made is small, but two of these hinged plates would be left in position, the others being swung free, so that the two hinged plates left in position will enter the space between the abutting teeth, substantially down to the gum. Thus when it is desired to remove

the tray from the mouth of the patient, it is a simple matter to separate the two halves sidewise, and remove the same with no discomfort or pain to the patient.

A further feature of my present invention consists in the provision of a novel form of combined clamp and handle for my impression tray. This handle is so formed that it will act as a clamp to hold the two body portions together, until the plastic material has "set", whereupon, if desired, the handle may be removed from the tray, thus making a much more comfortable device in the patient's mouth. I believe that my present sectional impression tray is new, and I therefore wish to claim the same herein broadly. I also believe that my present form of combined clamp and handle is new, and I also wish to claim the same broadly herein.

A further feature of my present invention consists in the provision of an impression tray, which, after a model has been made therefrom, can be retained, and further models made from the first impression.

A further advantage of my present invention, is that the patient is not forced to undergo the unpleasantness of the dentist being required to take more than one impression of the same space, which is at present requisite, due to the breaking of the impressions in the present trays, and the inability to correctly join the impression after being removed.

My present novel tray is preferably constructed of a light metal, such as aluminum, for facility in handling and lightness of weight in the patient's mouth.

A further advantage of my present invention is that there is no danger to the patient, as heretofore, from small particles of the plaster of Paris chipping or breaking away and lodging in the patient's throat. Heretofore this has been a serious consideration, and frequently has resulted in grave danger to the patient.

It will thus be seen that I have devised a novel sectional impression tray, one which is light in weight, economical to manufacture, and of great utility in the dental art.

Referring to the drawings, illustrating a preferred embodiment of my invention,

Fig. 1 is a plan view of my novel tray in inverted position;

Fig. 2 is a cross sectional view on the line 2-2 of Fig. 1;

- Fig. 3 is a top plan view of my tray;
 Fig. 4 is a side view;
 Fig. 5 is a cross sectional view on the line 5—5 of Fig. 3;
 5 Fig. 6 is a side view of my novel clamp and handle;
 Fig. 7 is a longitudinal cross sectional view of my novel impression tray in actual operation; and
 10 Fig. 8 is a cross sectional view on the line 8—8 of Fig. 7.

As shown in the drawing, my novel sectional impression tray comprises two body portions 1 and 2, the portion 1 having enlarged ends 3, 3 equipped with bevelled tongues 4, 4, and adapted to cooperate with correspondingly bevelled grooves 5, 5 in the enlarged ends 6, 6 of the portion 2. The body portion 1 has, equidistant its ends, a flattened outwardly extending projection 7, this projection 7 having thereon a catch 8. The body portion 2 has a corresponding projection 9, and catch 10. When the tray is assembled, as shown in Figs. 1 and 3, I apply my novel clamp and handle thereto, to further hold the tray in assembled position. My novel clamp comprises a handle member 12, pivoted to the clamp 14 by means of a rivet, or the like, 15, so that the handle 12 may be swung in any desired position around the clamp 14. This clamp 14 is of spring metal, and is curved at its lower ends to form a locking hook 16. When positioned on the tray, the clamp will be "sprung" over the sides of the tray, and the locking hook 16 will thereupon engage with the catches 8 and 10 on the side of the projections 7 and 9, thus securely holding the tray in closed position.

As clearly shown in the drawings, I provide a plurality of swinging plates, for example 20, 21 and 22 on the body 1, and 23, 24 and 25 on the portion 2. These plates are swingingly mounted on wires 26 and 27, which wires are held in position in the enlarged ends 3 and 6 of the portions 1 and 2. The swinging plates above referred to are formed substantially triangular where they are connected to the rods. For example, plates 20 and 23 are provided with flat faces 30 and 31, which faces are adapted to form a closure, so that the tray will be in proper condition for receiving the plaster of Paris or other impression-making material. On the inside of the tray, at the ends outside of the swinging plates, I provide ridges 32, 32 and 33, 33, of less height than the plates 20 and 23, for example.

When the tray is thus in assembled position, it being desired to make an impression of a cavity in a patient's mouth, the space between the abutting teeth is calculated, and as shown in Fig. 7, the three center plates are left in normal position, while the two plates at either side of these three plates are

swung upwardly, out of position, so that the three plates 20, 21, and 40, will fit into the space between the abutting teeth 41 and 42, projecting downwardly substantially to the gum 43. The normally upper ends of the inverted plates 22, 44, 45, and 46, are now projecting downwardly within the mold, as shown, for example, at 50. The plaster of Paris 51 fills all spaces and interstices not occupied by the plates or ridges on the inside of the tray. It will be apparent, on an inspection of Fig. 7, that there is provided along the entire length of the tray, a line of plates or ridges, which will cause a straight cleavage of the plaster of Paris when the tray is separated and removed from the mouth of the patient. When the plaster has begun to "set", the handle and clamp may be removed, and the holding of the tongues and grooves will be sufficient to retain the tray in its position in the patient's mouth. When the plaster has completely set, and the dentist desires to remove the tray, with the impression therein, the insertion of a knife blade, or other instrument into the groove 80, as shown in Fig. 3, and slight pressure thereon, will be sufficient to cause a complete separation of the two halves of the tray, together with a cleavage of the plaster contained therein, upon an even line. Thereupon, when the halves of the tray are removed sidewise from the portion of which the impression has been taken, there will be left no particles or débris of the plaster in the patient's mouth. Thereupon, the dentist 100 reassembles the two sections together, greases the same, and pours in the material to make the model desired.

Fig. 8 illustrates in cross section the general position of the swinging plates, when they are swung out of operative position.

It will thus be apparent that I have provided a novel sectional impression tray, which is a great advance in the dental art, and one, which, because of its construction 110 to fit the particular space or cavity to be impressed, is of great utility and efficiency in this art.

It is also within the province of my invention to provide fewer swinging plates, 115 if desired, and when it is desired to take an impression of a larger space than the plates would normally fill, to slide a portion of these plates along the wire, until the plates present an area sufficient to fill, longitudinally, the cavity desired to be impressed.

While I have described my invention somewhat in detail, it will be appreciated that I may vary the size, shape, and arrangement of parts, within wide limits without departing from the spirit of the invention. It will also be appreciated that while I have illustrated my novel impression tray of a size adapted to make an impression of a portion only of a patient's mouth, I may make such 130

impression tray of a size to fit the entire upper or lower jaw, and to take impressions of several cavities or spaces simultaneously.

My invention is further described and defined in the form of claims as follows:

1. A sectional impression tray, comprising two interlocking sides, and a plurality of medial ridge forming plates carried between said sides, said plates being movable into and out of operative position.

2. A sectional impression tray, comprising two interlocking sides, and provided with a plurality of adjustable plates and ridges, to form a continuous medial ridge of varying depth inside of said tray.

3. A sectional impression tray, comprising two interlocking sides, wires secured to said sides, and a plurality of plates mounted on said wires, movable into and out of operative position.

4. A sectional impression tray, comprising two interlocking sides, wires secured to

said sides, a plurality of plates mounted on said wires, and adapted to penetrate a space between abutting teeth.

25

5. A sectional impression tray, comprising two interlocking sides, wires secured to said sides, a plurality of plates mounted on said wires, and a predetermined number of said plates being adapted to penetrate a space between abutting teeth.

6. A sectional impression tray, comprising side portions having interlocking tongues and grooves thereon, wires positioned on said sides, a plurality of swingable plates mounted on said wires, said plates being so constructed that whether in or out of operative position a continuous medial ridge along the inside of said tray is provided.

In testimony whereof, I have signed my name to this specification.

DAVID BARATT.
